UNITED STATES PATENT OFFICE.

WILLIAM A. JOY, OF SPRINGFIELD, ILLINOIS, ASSIGNOR OF ONE-THIRD TO ERNEST A. YOUNG AND ONE-THIRD TO HOMER V. HAYNES, BOTH OF SPRINGFIELD, ILLINOIS.

FLEXIBLE SHINGLE.

Application filed October 7, 1924. Serial No. 742,179.

To all whom it may concern:

Be it known that I, WILLIAM A. Joy, a citizen of the United States, residing at Springfield, in the county of Sangamon and State of Illinois, have invented a new and useful Flexible Shingle, of which the following is a specification.

My invention relates to improvements in flexible shingles of metal, or asbestos, or other composition.

The purpose of the invention is to provide improved means for holding down the lower corner of each shingle to prevent warping or curling of the shingles and at the same time maintain the symmetrical diamond-shape arrangement of the laid shingles.

I attain this purpose by the means illustrated in the accompanying drawing in which—

20 Figure 1 is a top plan of part of a roof covered with shingles embodying my invention; Figure 2 is an enlarged top view of a single detached shingle; Fig. 3 is an under-side view of the same detached shingle; 25 Fig. 4 is an enlarged vertical section taken on the line 4—4 of Fig. 3; Fig. 5 is an under-side view of a shingle of modified construction embodying my invention; Fig. 6 is an enlarged vertical section taken on the 30 line 6—6 of Fig. 5; and Fig. 7 is an enlarged vertical section taken on the line 7—7 of Fig. 5. The same reference numerals designate the same parts in all the views.

35 The shingles 8 are preferably of asbestos composition and each shingle is square and has four right-angle corners in order that the symmetrical arrangement shown in Fig. 1 may be maintained when the shingles are 40 laid on the roof. A starter-strip 9 consisting of flexible roofing of the same material as the shingles is laid along the lower edge of the roof. Parts of the first, second and third rows of shingles lie on the starter strip. The first or bottom row will consist 45 of approximately half-shingles; all the other rows will consist of whole square shingles of uniform size. One shingle of preferred construction is shown in Figs. 2, 3 and 4. On the underside of the shingle is 50 a triangular flap or fastening member 10 of the same material as the body of the shingle. The edges of the flap which converge at its right angle coincide with the converging edges of the lower end of the shingle. The asbestos composition of the shingles is

naturally sticky. There is practical advantage in making the flap 10 of the same material. The advantage is that the movable members of the flap, having considerable contact area will adhere to the interlocking shingles and will soon after laying, become practically cemented thereto, thus preventing the breaking or pulling out of the flap. There is also practical advantage in the form of the flap, in that it affords larger contact area than has hitherto been available.

55 A filler or spacer 12 of the same material as the body of the shingle is interposed between the flap 10 and the shingle-body 8. A staple 13 extends through the flap, through the spacer, and through shingle-body and is clinched on the upper side of the shingle and unites the parts firmly. 75 The length of the body of the staple is in a diagonal line connecting the upper and lower corners of the shingle. The spacer 12 is preferably of the same thickness as the shingle and the inclined upper edges of the 80 spacer serve as guides in placing the adjacent shingles which are overlapped by the shingle in question. The particular position of the staple, in a diagonal line of the shingle, is of importance because it facilitates manual adjustment of the free corner-members 18 of the flap 10 relative to the body of the shingle so that the adjacent parts of the interlocking shingles may be 85 easily inserted in the space between the 90 shingle body and the flap. The flap member 10 and the spacer 12 are omitted from the shingles which are used in the first row of whole shingles and the lower ends of the 95 shingles in said first row are connected with the half-shingles by cement 14.

100 In laying the shingles on the roof, beginning at the lower edge of the starter strip, the row of half-shingles will be placed with their right and left corners in line with each other along the lower edge of the starter strip and will be secured by nails 15 driven into the sheathing of the roof. The first course of whole-shingles will then be placed overlapping the course of half-shingles and 105 with their right and left corners in line with each other.

110 The whole-shingles of the first course will have no flaps and no spacers and the lower corners of the respective shingles will be secured on the half-shingles by cement 14. The shingles will be laid in horizontal

courses each course comprising a number of shingles placed with their right and left corners in line with each other. The first course will comprise half-shingles placed with their right and left corners in line with each other along the lower edge of the starter strip. The first course of whole-shingles will be placed with their right and left corners in line with each other and the respective shingles will be secured by nails 15 at the upper corners of the shingles. The whole-shingles comprised in the second course will be placed with their right and left corners in line with each other and their lower margins overlapping the upper margins of the adjacent two shingles of the next lower course. Before nailing the shingles of the second course each shingle of that course will be moved upwardly to cause the flap members 18 of the flaps 10 of the respective shingles to underlie the two adjacent shingles of the next lower course and when the shingles have been interlocked as described a nail 15 will be driven through the upper corner of each shingle in the course to hold it in place; and each successive course will be placed and secured in like manner.

Relatively thick shingles are used in the preferred construction shown in Figs. 1, 2, 3 and 4 and described above.

I have found by experiment that if relatively thin shingles are used the construction shown in Figs. 5, 6, and 7 and now to be described gives very satisfactory results.

The shingle 19 is thinner than the shingle 8 but in all other respects is the same as that shingle. The flap 20 is the same as the flap 12 except as to thickness and the converging inclined edges of the flap coincide with the inclined converging edges of the shingle. The free terminal members 21 of the flap 20 are similar to the terminals 18 of the flap 10. Dotted lines 22 Fig. 7 indicate the manually adjusted position of the members 21 relative to the shingle body 19.

A staple 23 coincides with a diagonal line of the shingle body and extends through the flap and the body and is clinched on the upper face of the shingle. The procedure in laying the modified shingles is the same as in laying the shingles of preferred construction.

I am aware of the prior use of shingles having bent-under flaps provided with laterally extended metal strips which engage the adjacent interlocking shingles, but that construction is objectionable because the bend of the turned under part gives the shingle the appearance of being cut off and

the cut off appearance detracts from the symmetry of the diamond arrangement of the shingles on the roof.

In my construction the attractive diamond arrangement of the shingles is intact on the whole of the roof. Another feature of my improvement is that the converging edges of the flap coincide with the converging edges of the body of the shingle, the spacer facilitates the interlocking of the shingle and there is no necessity to use any metal strip, or any other extraneous interlocking member. This improved and simplified construction is of practical value because it adds to the attractive appearance of the roof as a whole, is less expensive, and more convenient to handle than a shingle having a metallic or other extraneous interlocking element.

I am also aware of the prior use of shingles notched at the lower corner but such notched shingles are subject to the same objection of marring the appearance of the diamond arrangement of the shingles on the roof.

Having fully described my invention, what I claim as new and desire to secure by Letters Patent is:

1. A flexible shingle comprising a flat square body having four right-angle corners; a triangular flap of the same material as the shingle body and having converging inclined edges coinciding with the converging inclined edges of the body; a spacer of the same material interposed between the shingle body and the flap and having inclined upper edges effective to guide the placing of interlocking shingles; and a staple in line with a diagonal of the body and extending through the flap, the spacer, and the body and clinched on the upper face of the body to unite the parts firmly.

2. A flexible shingle comprising a flat rectangular body of flexible material; a triangular flap of the same material having converged edges coinciding with the converged edges at the right angle of the lower corner of the body, also having free angular terminal members serving as interlocking means and adapted to cling to interlocking shingles and manually movable relative to the shingle-body; a spacer of the same material as the shingle body; and a staple in a diagonal line of the shingle-body and extending through the flap, the spacer, and the body and clinched on the upper face of the shingle-body to firmly unite the parts.

In witness whereof I have hereunto signed my name at Springfield, Illinois, this 26 of September, 1924.

WILLIAM A. JOY.
